UNITED STATES PATENT OFFICE.

WILLIAM H. STOBIE, OF WATERVILLE, MAINE, ASSIGNOR TO HOLLINGSWORTH & WHITNEY COMPANY, OF WATERVILLE, MAINE, A CORPORATION OF MASSACHUSETTS.

APPARATUS FOR DISINTEGRATING FIBROUS MATERIAL.

1,263,139.

Specification of Letters Patent. Patented Apr. 16, 1918.

Application filed November 24, 1914. Serial No. 873,842.

To all whom it may concern:

Be it known that I, WILLIAM H. STOBIE, a citizen of the United States, and a resident of Waterville, county of Kennebec, State 5 of Maine, have invented an Improvement in Apparatus for Disintegrating Fibrous Material, of which the following description, in connection with the accompanying drawings, is a specification, like characters 10 on the drawings representing like parts.

My invention relates to an improvement in the process of disintegrating fibrous material used in the manufacture of pulp, the object being to divide, separate, or roughen 15 the fibers without breaking or cutting them, thereby producing a stock that will felt better than the stock from an ordinary beating engine.

I have shown one illustrative embodiment 20 of my invention in the drawings hereto annexed, wherein,

Figure 1 is a side elevation of an embodiment of my invention showing a stock vat, a stock pump, a nozzle or delivery head 25 and targets;

Fig. 2 is a relatively enlarged view looking in the direction of the arrow in Fig. 1;

Fig. 3 is a side elevation of the parts shown in Fig. 2;

Fig. 4 is a relatively enlarged plan view 30 of a section of the face of the target; and

Fig. 5 is a cross section taken on the line 5-5 of Fig. 4.

The type of disintegrating apparatus 35 hereinafter described is the same in broad principle as disclosed in my Patents Nos. 1,099,581; 1,099,579; 1,062,307; and 1,099,578 in so far as a disintegrating surface is employed against which the pulp stock is to 40 be projected. I have found, however, that by arranging two or more targets in different planes in such position that the pulp stock upon being projected against one target may glance or carom to the surface 45 of another, the process of disintegration is much quickened, and the final product thereof improved.

Referring to the drawings, a usual stock vat is indicated at 1, a usual pipe leads 50 therewith as indicated at 2 feeding into a usual pump 3 which is, in turn, connected by the pipe 4 to a delivery head 5.

Nozzles, or delivery heads, in this art have usually been constructed in the shape of a

tapering cone, but I find that advantages 55 arise from constructing my nozzle or delivery head in the general shape of a T which may be attached to the end of the pipe 4 as shown and which may be provided with a slot 6, through which pulp stock may 60 be forced. By thus providing a T headed slotted delivery head I am enabled to increase the amount of stock which may be projected against the targets without decreasing the efficacy of the targets in the 65 disintegration of said stock.

For purposes of illustration I have shown two targets 7 and 8 appropriately mounted within the vat 1, the upper target 7 being positioned at an incline in front of the delivery head 5, and the lower target 8 at a different incline in such a position that the projected stock being dashed against the target 7 glances therefrom and strikes against the target 8, thence falling again 75 into the tank.

For purposes of specific illustration I have shown the surfaces of the targets 7 and 8 as serrated, the angular edges 9 of the serrations 10 lying preferably directly toward 80 the top of the targets (as best shown in Fig. 4) in such a manner that the stock when it is precipitated against the targets must encounter the edges of the serrations rather than the flat sides thereof. I find 85 that this arrangement expedites the disintegration of the pulp stock.

Of course it is evident that the targets may be provided with other types of disintegrating surfaces without departing from 90 the spirit of my invention; and that more than two angularly disposed targets may be employed according to the needs of a specific occasion.

Having described my invention, I claim: 95

1. In an apparatus for disintegrating fibrous material, in combination with a source of stock supply, means for forcibly projecting said stock against a target, means for spreading said forced stock into a relatively thin stream or moving body, and a plurality of angularly arranged targets 100 against which said stock may be forced.

2. In an apparatus for disintegrating fibrous material, a stock vat, a pump and 105 stock-conducting pipe connected therewith, said conducting pipe communicating with an elongated opening for the egress of

pumped stock, and a plurality of angularly arranged disintegrating targets positioned within range of said opening whereby said stock may be projected against said targets 5 or one of them.

3. In an apparatus for disintegrating fibrous material, in combination, a source of stock supply, an elongated stock egress opening communicating therewith, angularly arranged targets against which said stock may be projected through said egress opening, and means for so projecting said stock.

4. In apparatus for disintegrating fibrous material, in combination, a source of stock supply, a stock egress opening communicating therewith, angularly disposed targets against one or more of which said stock may be projected through said egress opening, 15 and means for so projecting said stock.

5. In an apparatus for disintegrating fibrous material, in combination, the stock vat 1, the conduit 2, 4, the pump 3 connected therewith, the delivery head 5 having an 20 elongated aperture 6, and the angularly 25

disposed targets 7, 8 positioned within range of said aperture.

6. In an apparatus for disintegrating fibrous material, a stock vat, a pump connected therewith, a T shaped slot-aperture 30 delivery head, and a plurality of angularly arranged disintegrating targets positioned within range thereof.

7. In an apparatus for disintegrating fibrous material, a stock vat, a pump connected therewith, a T shaped slot-aperture delivery head, and a plurality of angularly arranged disintegrating targets positioned within range thereof, said targets being provided with edged projections thereon so arranged that their edges are presented toward the line of projection of pulp stock 35 passing through the delivery head.

In testimony whereof, I have signed my name to this specification, in the presence of 40 two subscribing witnesses.

WILLIAM H. STOBIE.
